SPRAY NOZZLE

Robert Wilson De Baugh, Baltimore, Md., assignor, by direct and mesne assignments, to American Cleaning Equipment Company, Baltimore, Md., a corporation of Maryland

Application April 15, 1938, Serial No. 202,326

8 Claims. (Cl. 141—1)

This invention relates to spray nozzles for use in cleaning and more particularly to such nozzles as employed in washing drums, tanks, and the like.

It is well known that tanks, drums, or barrels in which oil or other liquids are shipped or stored are costly to manufacture and consequently in the interest of economy should be used a plurality of times. However, since these tanks cannot be completely emptied of their contents by ordinary discharge means, it is necessary that some means be provided to wash off any residue adhering to the inner walls thereof prior to reuse. Further, when the washing operation has been completed, it becomes necessary to remove the dislodged sludge and dirt together with the washing fluid from the bottom of the container.

Heretofore it has been the practice to provide complex machinery to effect such washing of tanks, barrels, and the like, means being provided to move the container with respect to a fixed spray nozzle from which a cleansing fluid is discharged and to effect a discharge of the dirt and washing medium after the cleansing operation. This machinery, although effective in cleaning small drums and barrels is not adaptable to cleaning tanks, ships holds, and the like where the size of the container is such that it cannot be moved with respect to the nozzle. Furthermore, if an ordinary hose is used to clean large vessels, there is presented the problem of disposing of the dirt and washing medium after the cleansing operation.

It is therefore an object of the present invention to provide a cleaning nozzle adaptable for use in all sizes and types of containers.

The present invention further contemplates the provision of means cooperating with a reversible flow fluid supply under pressure, whereby an effective and efficient washing of a drum or tank may be accomplished and further the provision of means for withdrawing the dirt, oil, etc. washed from the sides of the tank together with the detergents fluid used, after the cleansing has been completed and without changing the position of the drum. Additionally the means provided in the present invention permit a diffusion of the cleaning fluid under a predetermined pressure so that the distribution of the washing medium will be most efficient and effective. This is done by the provision of a suitable valve arrangement and a cooperating arrangement of discharge apertures.

In one embodiment of this invention, the fluid distribution is further assisted by means to cause

the nozzle to swirl so that the washing fluid may be activated by centrifugal force as well as the pressure from the fluid supply source.

In view of the fact that the nozzle forming the subject matter of the present invention can be attached to practically any type of conduit, either flexible or rigid, it is possible to adapt its use to almost any size closure. Naturally, the length of the rigid portion of the connecting conduit will vary in response to the size of the container as the latter gives rise to the necessity for a longer guiding handle for accurately directing the cleansing streams to the walls and bottom of the container.

The means by which the foregoing objects are accomplished consist in the provision of a nozzle adapted to fit on any conventional reversible flow fluid supply conduit such as a hose or the like, the nozzle containing a valve arrangement such that the fluid flowing into the nozzle will be conducted to the spray apertures at predetermined pressure, and when the flow is reversed, a suction orifice will become operative and effectively withdraw the dirt and washing fluid from the vessel being cleaned.

Further objects and advantages of the invention will be apparent from a consideration of the detailed description following in conjunction with the accompanying drawings in which:

Fig. 1 is a view of the device in operation; 30

Fig. 2 is a vertical sectional view;

Fig. 3 is a section taken along the line 3—3 of Fig. 2;

Fig. 4 is a sectional view of a modification of the invention; 35

Fig. 5 is a sectional view taken along the line 5—5 of Fig. 4;

Fig. 6 is a plan view of the suction orifice;

Fig. 7 is a front elevation of the suction orifice;

Fig. 8 is a sectional view of a modification of the invention showing an alternate device for rotating the nozzle during operation; and 40

Fig. 9 is a sectional view taken along the line 9—9 of Fig. 8.

Referring to the drawings, Fig. 1 is a view of the device in operation showing a suitable pump 1, a supply conduit 2, a nozzle 3, and drum 4. In Figs. 2 and 3, there is a detailed showing of the structure of one embodiment of the nozzle 3 constituting a part of the subject matter of the present invention. This nozzle is composed of a shell 5 having an interiorly threaded upper portion 6, and a generally conical lower wall 7, this latter wall being provided with a series of discharge apertures 8. At the base of the lower 55

wall 7, there is a suitably fastened plug 9 provided with a concentric aperture and interiorly threaded at its upper end, and at its lower end there is suitably formed a flared orifice 10 which 5 may be made by crimping together the walls of the plug 9.

In threaded engagement with the interior threads of the drilled plug 9, there is a tube 11 which communicates with a valve plate 12 and 10 is spot-welded thereto as shown at 13. As will be noted from a consideration of the drawings, valve plate 12 is threaded in a manner adapted to cooperate with the threads of upper wall 6 of the housing 5 of the nozzle as a whole. Since 15 the conduit 11 is welded to the valve plate 12, it will be seen that the valve plate and the conduit may both be screwed into operative position by a single operation.

Valve plate 12 is provided with a seat 14 adapted to receive a ball 15, which ball acts as a valve to control the flow through conduit 11. Forming a cage for this valve are a series of pins 16 which maintain it in position and insure its proper seating.

25 In the same valve plate 12, there is suitable seating 17 for a spray valve 18. This latter valve seats against the lower side of valve plate 12, said spray valve 18 being provided with a stem 19 supported by a suitable bearing defined by valve 30 plate 12. At the upper end of stem 19 there is a key 20. Between said key 20 and the upper surface of valve plate 12, there is disposed a helically wound spring 21 which is disposed around valve stem 19. The upper wall 6 of the 35 nozzle 3 is also adapted to receive a sleeve 22 which is provided with an annular threaded shoulder 23 which shoulder threadedly engages the upper wall 6 of housing 5 of the nozzle as a whole.

40 In Figs. 4 and 5 there is shown a modification of the present invention in which provision is made for a means to rotate the nozzle, said means being responsive to the pressure and the fluid flow through the nozzle. The lower portions of nozzle 45 3, the valve arrangements, and the orifices are the same as those discussed above in connection with Figs. 2 and 3. The interiorly threaded upper wall 6 of housing 5, however, is somewhat longer and is adapted to receive in addition to 50 the valve plate 12 and the sleeve 22 a rotor supporting disc 24 which is screwed into the chamber defined by the upper walls 6 of housing 5 between the valve plate 12 and the annular shoulder 23 of sleeve 22. Within the upper wall 6 of 55 housing 5, there is a suitable aperture at 25 adapted to receive a key 26, said aperture cooperating with another aperture in rotor supporting plate 24, said two apertures when in alignment being adaptable to receive key 26, whereby 60 the rotor is maintained in fixed position within the nozzle 3.

As is more clearly shown in Fig. 5, rotor supporting plate 24 has cut therein a series of radially extending slits and a series of cooperating 65 arcuate slits; by this means it is possible to constitute the rotor support a blank from which the impeller blades 27 are made by simply bending the same in a manner such that the advantages incident to a turbine may be obtained.

70 Positioned within the concentric passageway in the sleeve 22 is an additional sleeve 28, the latter being provided with an outwardly extending annular flange 29 to engage the undersurface 75 of sleeve 22. The upper ends of sleeve 28 are outwardly threaded and are adapted to receive a

collar 30 which is inwardly threaded. By this means a bearing surface is made between sleeve 28 and sleeve 22 and axial thrust is taken by the lower edge of collar 30 or by the annular flange 29 on sleeve 28 as the case may be. By this construction it will be seen that the nozzle 3 is freely rotatable in response to the action of the fluid pressure on impeller blades 27.

Instead of the blades 27, as shown in Figures 4 and 5, a rotor of the type shown in Figures 10 8 and 9 may be employed. This rotor consists of two volute impellers 32 keyed to the side wall of shell 5. The charge end of the impellers lies free within sleeve 28 around which the nozzle as a whole rotates. The structure of this modification in other respects corresponds exactly to that shown in Figures 4 and 5 and corresponding reference numerals have been used.

Referring now to Figs. 6 and 7, there is shown the detailed structure of suction orifice 10 which is defined at the lower end of concentrically apertured plug 9. This structure has the advantage of being rounded as shown at 31 so that it may more readily engage the rounded walls of a tank or the like, and when resting on the bottom, 25 there is a little air space at the sides. The aperture 10 is generally longitudinal in shape which will prevent the entrance into the nozzle of any material tending to clog either the valves of the nozzle or the pumping system.

When the nozzle, as shown in Figs. 2 and 3, is put into operation by the flow of a fluid under pressure through the concentric aperture in sleeve 22, the fluid exerts its force against the upper wall of the spray valve 18, and when its pressure is sufficient to overcome the thrust of spring 21, the valve opens and the fluid enters the chamber defined by the lower portion 7 of the shell 5 and is extruded through the apertures 8 under pressure, thereby creating a spray by means of which the tank or closure is effectively cleaned. When the cleaning operation has been completed, and it is desired to remove the sludge, dirt, and washing medium from the closure, the flow is reversed. This results in the immediate closing of spray 45 valve 18 by both the action of the spring 21 and the sucking action of the pump. Since spray valve 18 is firmly seated against valve plate 12 at 17 during the suction operation, the chamber defined by the lower walls 7 of the shell 5 will be 50 inactive. Ball valve 15, however, will be lifted from its seat 14 in valve plate 12 and the fluid being exhausted from the tank will be drawn in through flared nozzle 9 and the chamber defined by tube 10 out through the opening adjacent 55 valve seat 14 and finally through the conduit connected to the nozzle at sleeve 22. This operation is continued until the contents of the tank are exhausted.

The modifications shown in Figs. 4 and 5 will 60 operate in a manner similar to those shown in Figs. 2 and 3, except that the fluid pressure on impeller blades 27 will result in the rotation of nozzle 3 on the bearing surface defined by sleeves 22 and 28. This action will be conducive to a 65 better fluid distribution in the cleaning operation and a better suction during the exhaust operation, since there is added to the pressure or suction the centrifugal force developed by the rotation of the nozzle.

In operation, the device shown in Figures 8 and 9 is quite similar to that shown in Figures 4 and 5, the driving force resulting from the impinging of the fluid from the orifices at the end of the volute tubes 32 against the wall 6.

I claim:

1. A combination suction and discharge nozzle adapted for use in cleaning tanks and the like, comprising a combination intake and exhaust 5 passageway communicating with separate chambers, one of said chambers being provided with a plurality of discharge orifices, the other of said chambers being disposed within said first chamber, said second chamber being provided with a 10 single intake orifice, all valve controlling the fluid flow through said second chamber into said passageway, and a spring thrust pressure responsive valve controlling the flow through from said passageway into said discharge chamber.

15 2. A combination suction and discharge nozzle adapted for use in cleaning tanks and the like, comprising in combination means defining intake and exhaust passageways, means in said passageways for selectively directing the flow of 20 fluid through said nozzle, and flow responsive means within said nozzle to rotate the same.

25 3. A combination suction and discharge nozzle adapted for use in cleaning tanks and the like, comprising in combination means defining intake and exhaust passageways, means in said 25 passageways for selectively directing the flow of fluid through said nozzle and a rotor keyed within said nozzle and adapted to cause the same to rotate as fluid is passed therethrough.

30 4. A combination suction and discharge nozzle adapted for use in cleaning tanks and the like, comprising in combination means defining intake and exhaust passageways, means in said passageways for selectively directing the flow of fluid 35 through said nozzle and a voluted tube keyed to said nozzle and adapted to receive a fluid passing through the nozzle to thereby cause the rotation of the latter.

40 5. A combined suction and discharge device for cleaning tanks and the like with fluids, comprising a fluid supply and withdrawal chamber, means defining intake and exhaust passageways in communication with said chamber, and means in said passageways for selectively permitting the flow of fluid through a passageway dependent upon whether fluid is supplied to or withdrawn 45 from said chamber.

45 6. A combination suction and discharge device for use in cleaning tanks and the like comprising

ing, means defining a chamber, means defining intake and exhaust passageways in communication with said chamber, means in an exhaust passageway for permitting flow therethrough from said chamber in response to positive pressure in the latter, and means in an intake passageway for permitting flow therethrough to said chamber in response to negative pressure in the latter, whereby the same device may be used for expelling detergent fluids and for removing the 10 fluids and dirt from the tank or the like being cleaned.

7. A combination suction and discharge nozzle for use in cleaning tanks and the like comprising, 15 means defining a chamber, means defining intake and exhaust passageways, ports in said chamber permitting communication between the same and said passageways, means in one of said ports for establishing communication between one of said passageways and said chamber in response to positive pressure in the latter, and means in another of said ports responsive to negative pressure in said chamber for establishing communication with another of said passageways, whereby the same nozzle may be used for expelling detergent 25 fluids and for thereafter removing the fluids and the dirt from the tank or the like being cleaned.

8. A combination suction and discharge nozzle for use in cleaning tanks and the like comprising, a primary chamber, an exhaust chamber provided with a plurality of discharge apertures, a suction chamber within said discharge chamber, said suction chamber being provided with a single orifice communicating with the outside of said nozzle, ports in said primary chamber permitting communication between the same and said exhaust and suction chambers, means in one of said ports for establishing communication between said exhaust chamber and said primary chamber in response to positive pressure in the latter, and means in the other of said ports for establishing communication between said suction chamber and said primary chamber in response to negative pressure in the latter, whereby the same nozzle may be used for expelling detergent fluids and for thereafter removing the fluids and the dirt from the tank or the like being cleaned.

ROBERT WILSON DE BAUGH.
